Edward Andrews.

United States Patent Office.

EDWARD ANDREWS, OF POTTSVILLE, PENNSYLVANIA.

Letters Patent No. 76,876, dated April 21, 1868.

IMPROVED WINDOW-SASH HOLDER.

The Schedule referred to in these Letters Patent and making part of the same.

TO ALL WHOM IT MAY CONCERN:

Be it known that I, EDWARD ANDREWS, of Pottsville, in the county of Schuylkill, in the State of Pennsylvania, have invented a new Mode of Holding Window-Sashes; and I do hereby declare that the following is a full, clear, and exact description thereof, reference being had to the accompanying drawings and to the letters of reference marked thereon.

Figure 1 is a view showing the sash shut, held in place by the rack C, and the mode of application complete.

Figure 2 is a view of circular box, A, showing the slot for rack C to slide through; also, the manner the latch B is held in place.

Figure 3 is an interior view of the box A, showing the spiral spring J operating against the latch B.

Figure 4 is a view of the latch B, showing the slot the rack C also slides in.

This invention consists in providing window-sashes with the means of being raised or lowered at pleasure without ropes or weights; also, securely fastening them in any place desired.

To enable others skilled in the art to make and use my invention, I will proceed to describe its construction and operation.

I construct the box A, having the slot, as shown at fig. 2, and the latch B formed as shown at figs. 3 and 4; also, having a slot in it to correspond with the slot in box A; the end of latch B sliding in lower part of the slot in box A, and the piston part working in cylinder part of the same, where it is operated upon by the spiral spring J, as shown at fig. 3; the upper box being secured to upper part of sash, D, and the upper part of the lower sash being provided with another of similar construction, secured in line with each other, so that the rack C passes freely through the slots in each. The rack C, having notches for the latch B to slip in, is fastened to the upper part of the window-frame, as shown at fig. 1.

The operation is as follows: The body of the finger being thrust under the projecting part of box A, the thumb pressing against the end of latch B, slides it out of the notch in the rack C, and allows the sash to be raised or lowered to any position. Then, by relieving the latch B, the spiral spring J forces the latch into the corresponding notch in rack C, thereby securely fastening the sash as desired.

The advantage of this arrangement is raising or lowering both sashes, and securing them, without ropes or weights, and preventing them from being moved from the outside.

Having thus fully described my invention, what I claim as new, and desire to secure by Letters Patent, is—

The arrangement and combination of the rack C, box A, latch B, and spring J, operating in the manner and for the purpose herein described and specified.

EDWARD ANDREWS.
